UNITED STATES PATENT OFFICE

EDWIN R. BEACH, OF NEW YORK, N. Y.

IMPROVEMENT IN COMBINED LAMP-STANDS AND MATCH-BOXES.

Specification forming part of Letters Patent No. 174,936, dated March 21, 1876; application filed November 2, 1875.

To all whom it may concern:

Be it known that I, EDWIN R. BEACH, of the city, county, and State of New York, have invented certain new and useful Improvements in Combined Lamp-Stands and Match Boxes, of which the following is a specification, reference being had to the accompanying drawings, and to the letters of reference marked thereon.

I am aware that match-receptacles have before been constructed in connection with the base of a lamp or candlestick, such as the invention of Thomas Shanks, patented January 19, 1858, the objection to most of these being their expensiveness and inconvenience. The object of this invention is to produce a substantial, cheap, and convenient receptacle for matches within the base of a lamp, drop-light, or other illuminating apparatus.

In the accompanying drawings, Figure 1 is a front elevation of my improved lamp-base. Fig. 2 is the match-receptacle connected therewith, and Fig. 3 is the bottom plate of the base. Fig. 4 is a view looking down upon the lamp-base, match-receptacle, and plate, as connected ready for use, the drawer or receptacle being represented as open.

Similar letters indicate similar parts.

e is a projection cast within the receptacle,

in which the hole *d'* is drilled or cast to receive the pin or pivot *d*, which is cast on the base *A*. *f* is a projection cast on the plate *F*, and is made hollow to receive the nut *G*, which screws on the bolt *e*, running through the stand *a*, base *A*, and plate *F*, holding them firmly together, and preventing the drawer *B* from sliding off the pivot *d*. Small corner-pieces are cast within the base *A*, to prevent the plate *F* from being drawn in too far, or from pressing too tightly upon the drawer *B*, which is thus left free to swing on the pivot *d*.

The advantages of this arrangement are, that the whole base can be cast without using a core, and that the drawer may be readily opened by pressing upon it back of the pivot *d*; that it is a convenient and useful attachment to a lamp for the reception of matches.

Having thus described my invention, I claim as new and desire to secure by Letters Patent—

The pivoted match-receptacle *B* within the base of a lamp, drop-light, or other illuminating apparatus, constructed and operated substantially as described.

E. R. BEACH.
